GEORGE P. PILLING AND CHARLES J. PILLING, OF PHILADELPHIA,
PENNSYLVANIA, COPARTNERS TRADING AS GEORGE P. PILLING &
SON.

DESIGN FOR A BLANK FOR SPECULUM-BLADES.

SPECIFICATION forming part of Design No. 35,229, dated October 29, 1901.

Application filed August 5, 1901. Serial No. 70,985. Term of patent 7 years.

To all whom it may concern:

Be it known that I, CHARLES J. PILLING, a citizen of the United States, residing at the city of Philadelphia, State of Pennsylvania, have invented and produced a certain new and original Design for a Blank for Speculum-Blades, of which the following is a full, clear, and exact description, reference being had to the accompanying drawings, forming a part of this specification.

In said drawings, Figure 1 is a plan view of my blank, and Fig. 2 is a side view thereof.

My invention consists of the design in novel external outline, planular shape, or configuration of the sheet-metal blank shown in Fig. 1, from which the speculum-blade is produced when "struck up" by dies in the usual manner of producing metal shapes from sheet-

metal blanks. In its essentials it comprises a longitudinally-straight portion A, rounded at its outer end *a* and slightly curved at its opposite end *b*, with opposite narrow wing-like extensions *c c* proceeding from the base of the portion A and terminating in ears *d d*, the union of the portions *c c* with the portion A being on a curved line.

I claim—

The design for a blank for speculum-blades, substantially as shown and described.

In testimony whereof I have hereunto affixed my signature this 24th day of July, A. D. 1901.

CHARLES J. PILLING.
